FIG. 8. ATTORNEY

UNITED STATES PATENT OFFICE

2,311,029

GAME

Charles E. Cele, Portland, Oreg.

Application May 16, 1942, Serial No. 443,250

1 Claim. (Cl. 273—126)

This invention relates generally to amusement devices and particularly to a game.

The main object of this invention is to construct a game board by means of which may be simulated the conditions surrounding air raids.

The second object is to construct a game of the class described involving skill and chance and in which two, three or four players may engage.

The third object is to construct an improved form of playing piece and projecting mechanism.

These and other objects are accomplished in the manner set forth in the following specification as illustrated in the accompanying drawing, in which:

Fig. 1 is a plan of a game board with the minute details omitted.

Fig. 2 is a section taken along the line 2—2 in Fig. 1.

Fig. 3 is a fragmentary plan of one corner of the board.

Fig. 4 is an enlarged plan showing one quadrant of the circular center-piece of the board.

Fig. 5 is a plan of one of the pieces referred to as a bomb.

Fig. 6 is a quadrant shaped group of pieces of cardboard used for blacking out section of an area under attack.

Fig. 7 is a side elevation of Fig. 6.

Fig. 8 is a side elevation of one of the playing pieces with a portion thereof broken away in section.

Similar numerals refer to similar parts throughout the several views.

Referring in detail to the drawing there is shown a base 10 around whose outer edge is secured a rail 11 whose inner side 12 has secured thereto a resilient lining 13 of rubber, felt or other suitable material.

In the center of the playing surface 14 which is formed on the top side of the member 10, is disposed a circular center-piece 15 which is divided into quarters by the intersecting walls 16 forming the blue quadrant 17, the yellow quadrant 18, the red quadrant 19 and the green quadrant 20.

In each corner of the board is formed a playing field which extends from the line 21 to the opposite rail 11. The field is bounded on one side by a rail and on the opposite side by line 22 and is subdivided longitudinally by line 23. Cross lines 24 divide the field into the zones 25 to 41, inclusive, having the various markers 42. Markers 42 consist of circles within which are shown a desired number or character. Various sections 24 to 41 inclusive have a name 43 indicated there-

on and the result of the shot 44 is also indicated in each zone.

It is desirable to color the surface of the zones from 25 to 41 and the area 45 a color corresponding with the one shown in the areas 46, 47, 48 and 49. In each area is shown a plan of an airplane 50 on whose wings 51 are mounted the screw eyes 52 to which are attached the elastic bands 53.

10 The playing piece consists of a circular disc 54 having a groove 55 formed around same to receive the rubber band 53. An opening 56 is formed in the center of the disc 54 and its edge 57 is rounded to prevent injury to the fingernails of the player.

In Fig. 5 is shown a bomb 58 which is made of cardboard or other similar material, of which the player is provided with ten.

In Figs. 6 and 7 are shown a group of pieces 20 of cardboard shaped to cover the various subdivisions of the areas 17 to 20 inclusive. The piece 26—A is of a shape to cover the corresponding area 26—B on which is illustrated some docks.

25 The piece 27—A is shaped to cover the area 27—B on which is illustrated a power plant. 29—A is a piece which covers the corresponding area 29—B on which is illustrated a naval base. The piece 30—A covers a corresponding piece 30—B on which is illustrated an airport. The piece 31—A covers a corresponding area 31—B on which is illustrated a school. The piece 32—A covers a corresponding piece 32—B on which is illustrated an industrial center.

35 The piece 33—A covers the corresponding area 33—B on which is illustrated the communication system. The piece 34—A covers the corresponding area 34—B which illustrates a warehouse district. The piece 35—A covers the corresponding piece 35—B which illustrates a railroad. The piece 37—A covers the corresponding piece 37—B on which is illustrated a munitions depot. The piece 38—A covers the corresponding piece 38—B on which is illustrated a bridge. The piece 41—A

40 covers the corresponding piece 41—B on which is illustrated a hospital.

45 It will be understood that the pieces shown in Fig. 6 are preferably black on one side and colored to correspond with the color used by the player to whom the pieces belong on the other side.

While it can be played in different ways, a representative form of play is as follows:

50 All of the pieces are removed from the board.

55 The player defending the yellow area 18 will have

in his possession a set of pieces as shown in Fig. 6 which are black on one side and yellow on the other. He will also have ten bombs 58. The other players will each have the same number of bombs and a set of the pieces as shown in Fig. 6 of their own particular color.

The player defending the yellow will now place his disk 54 against the rubber band 53 and draw it back with his fingers which is placed in the opening 56. He then releases the piece 54 causing it to strike the opposite wall 11 and rebound onto one of the areas 25 to 41, inclusive. If the disc 54 moves to the position shown at 54—A it is out of bounds and the player passes the disc to his left. If for example, it moves to the position shown in 54—B on the area 29, it is a hit on a naval base. The yellow player then places one of his bombs 58 on the naval base area 29—B of his left-hand, or blue, opponent. He also blacks out his own naval base 29—B by placing over it one of his cardboard pieces 29—A.

It will be noted that the area 29—B has marked thereon within a circle the number 10 which is the value of a hit on a naval base. A corresponding number could be placed on the piece 29—A if desired, to facilitate the totaling of the score.

A hit on the dock area 26 has a value of five; on the power plant 27, thirty. Stopping on the area 28 would be called a dud in which event, the play would be passed. A hit on area 30, which is an airport, would have a value of forty-five points. A hit on the area 31 would cause the player to lose two bombs as a penalty for hitting a school although he is awarded fifty-five points therefor. A hit on the area 32 which is an industrial center, awards the player twenty points. A hit on the area 33 which covers communications, awards the player thirty-five points.

A hit on the area 34 which is the warehouse district, awards the player fifteen points. A hit on the area 35, which is a railroad, awards the player twenty-five points. A hit on the area 36 means that the bomb has fallen in a lake and the player passes his play. A hit on the area 37, which is a munitions depot, awards the player forty points. A hit on the area 38, which is a bridge, awards the player fifty points.

5 A hit on the area 39, which is a neutral country, causes the player to lose one turn. A hit on area 40 is considered a good shot and enables the player to take two plays. A hit on the area 41, which is a hospital, causes the player to lose two bombs but awards him sixty points.

10 If the disc 54 touches a section that calls for a loss of bombs and that section has already been blacked out or destroyed in the opponents section, play is passed without loss of bombs as a penalty.

15 When one player has all of his areas either blacked out or destroyed by bombs, the game is finished and the numbers indicated on the blacked out areas are totaled. The one having the highest total is winner of the game.

20 Those areas upon which the bombs 58 rest are theoretically destroyed and therefore could not be blacked out at any later portion of the game and serve to prevent the player in charge of such areas from blacking them out by later plays and thereby gaining the advantage of the numbers displayed thereon.

25 Obviously the rules may be varied considerably without departing from the spirit of the invention.

I claim:

30 A game of the class described consisting of a board being arranged for a plurality of players, the position of each player including a plurality of illustrated areas of different sizes and shapes, each of said areas bearing a graphic illustration of a military objective and identifying number, each of said areas having removable cardboard 35 covers made therefor, and shaped to correspond with the areas, the top side thereof being black and having associated therewith a plurality of bombs, an elongated playing surface at the disposal of each player, said surface having subdivisions 40 identified to correspond with said graphically illustrated areas, the particular area being selected by means of a playing piece, the players 45 graphically illustrated area corresponding therewith being blacked out by its cover while the corresponding illustrated area of an opponent having placed thereon one of the bombs.
